UNITED STATES PATENT OFFICE.

JOHN H. BENTLEY AND THOMAS W. BENTLEY, OF PATERSON, NEW JERSEY.

HEDDLE FOR WEAVING GAUZES.

SPECIFICATION forming part of Letters Patent No. 410,483, dated September 3, 1889.

Application filed August 14, 1885. Serial No. 174,397. (No model.)

To all whom it may concern:

Be it known that we, JOHN H. BENTLEY and THOMAS W. BENTLEY, citizens of the United States, residing at Paterson, Passaic county, 5 State of New Jersey, have invented a new and useful Improvement in Heddles for Weaving Gauzes, of which the following is a specification, reference being had to the accompanying drawings, forming a part thereof.

Figures 1 and 2 of the drawings are diagrams of a combination of heddles heretofore used for weaving gauze, the heddle-shafts being shown in section and the heddles in the position occupied by them when the sheds are 10 formed. This combination consists of two full heddles $a' b' b^2$, half-heddles $b a^2$, and standards $a^3 b^3 a^4 b^4$ for one pair of warp-threads $c c'$. These heddles are generally arranged as shown in diagrams 1 and 2, there 15 being considerable space left between the inner full heddle $a' b^2$ and standards $a^3 b^3$ to throw the half-twist in the warp-threads in said open space and between the said full heddle and standard when the shed is open, 20 being as shown in Fig. 1.

To form the shed in Fig. 1, the full heddle $a b^2$ is raised by elevating its shafts $a^{12} b^{12}$ by the usual means employed therefor, taking with it in its upward movement the half-heddle b and the warp-thread c , the shaft b^{13} of 25 the half-heddle being raised simultaneously with shafts $a^{12} b^{12}$. The thread c , while the same is being thus elevated, passes from the left-hand side of thread c' under thread c' , and is raised on the right-hand side of warp-thread c' , as viewed from the front of 30 the loom. Shafts $a^{13} a^{14} b^{13}$, carrying the full heddle $a' b^2$ and its half-heddle a^2 , are depressed by the usual means, and the said heddle $a' b^2$ takes with it in its downward movement half-heddle a^2 and warp-thread c' , the warp c' being drawn from the right-hand side of warp-thread c and depressed on the 35 left-hand side of warp-thread c . These movements of the heddles and threads throw a half-twist f between heddles $a' b^2 a^2$ and standards $a^3 b^3$, in addition to crossing the warp-threads at the front for the introduction of the weft-threads. When the full 40 and half heddles are thus moved, the standard $a^4 b^4$ is slightly elevated by raising its

shafts $a^{42} b^{42}$ to raise its middle looped portion a^{15} out of the way of the shed.

To form the shed shown in Fig. 2, the heddle or standard $a^4 b^4$ is depressed by the usual means, and takes with it warp-thread c' . The said thread c' is depressed by this movement of the standard and takes with it in its downward movement half-heddle a^2 on the right side of warp-thread c , as viewed from the front of the loom, drawing the said half-heddle across and above the warp c from the position shown in Fig. 1. At the same time the full heddle $a' b^2$ is elevated to remove the loop or eye d out of the way of the shed. 55 The heddle or standard $a^3 b^3$ is elevated, drawing the warp-thread c and half-heddle b across from right to left beneath the warp c' and raising them on the left-hand side of warp c' . At the same time the heddle $a' b^2$ is depressed 60 to remove the loop or eye d out of the way of the shed.

This combination of heddles is objectionable, for the reason that it throws a half-twist or cross f in the warp-threads $c c'$ between the heddles, which occasions a small cramped shed, preventing a free movement of the heddles, and by reason of friction and chafing of the warp-threads thereon causing early fracture of the heddle-strands from excessive wear, making frequent changes of the heddles necessary, and frequently severing the warp-threads. 75

The object of our invention is to provide a new combination of heddles for weaving gauze, whereby the heddles are caused to throw the twist of the warp-threads on each side outside of the heddles, by which means a more extended and open shed is secured for the shuttle, and the heddles are left free to operate without the friction and strain from the warp-threads produced by the twisting or crossing of the warp-threads between the heddles by the pre-existing combination. These objects we attain by the arrangement 80 of heddles shown in Figs. 3 and 4 of the drawings, which are diagrams of heddles arranged according to our invention, the heddle-shafts being shown in section, and in all the figures of the drawings are shown in elevation the cloth-roller and warp-roller. 85

In diagrams 3 and 4 four full heddles $a' b'$,

$a' b^2, a^{39} b^{49}, a^{45} b^{55}$ and four half-heddles $b a^2$ $b^3 a^5$ are used for one pair of warp-threads $c c'$, this being in accordance with our invention, the full and half heddles being arranged, as 5 shown, with just enough space between them for the full heddles and half-heddles to operate without interference. The warp-thread c passes through half-heddle b on the left-hand side of heddle $a' b'$, on the right-hand 10 side of heddles $a', b^2, a^2, a^{39}, b^{49}$, and a^5 , through half-heddle b^3 , and on the left hand of heddles $a^{45} b^{55}$. Warp-thread c' passes on the left-hand side of heddles $b a' b'$, through half-heddles a^2 at the right-hand side of heddle $a' b^2$, on the right-hand side of heddle $a^{39} b^{49}$, and through half-heddle a^5 on the left-hand side of heddle $a^{45} b^{55}$. The heddle-shafts are connected with their respective dobby-hooks e by cords f , and with springs h 20 by cords f' , and are operated by the dobby and springs in the usual way, as are all the heddles and half-heddles in the different diagrams 1, 2, 3, and 4, the half-heddles passing through their respective loops, as shown. 25 In Fig. 3 full heddle $a' b'$ is raised, taking with it half-heddle b and warp-thread c , shaft b^{13} of the half-heddle b having been raised simultaneously with shafts $a^{12} b^{12}$. Thread c passes, in such movement of the 30 heddles and half-heddles, on the right-hand side of warp-thread c' . Heddle $a^{39} b^{49}$ is depressed at the same time to remove the loop d out of the way. The full heddle $a' b^2$ is depressed, and takes with it in its downward 35 movements half-heddle a^2 and warp-thread c' , which passes on the left-hand side of warp-

thread c . The full heddle $a^{45} b^{55}$ is elevated to remove loop d out of the way. The weft-thread is thrown in at this formation of the shed and those following in the usual way. 40

By this our invention the crossing of the warps in the formation of the shed is effected, as shown by the diagrams, outside of the heddles, by reason of the first and third sets of full and half heddles working simultaneously in opposite directions and acting upon one warp-thread, and the second and fourth sets of full and half heddles working simultaneously in opposite directions and acting upon the other warp-thread. The warp-threads are therefore operated in an improved manner, by which a more extended and open shed is secured for the introduction of the weft by the shuttle and a more free exercise of the harness and warps. 45 50

To form the shed in Fig. 4 the action of the heddle is reversed.

We claim—

In a loom for weaving gauze, the combination of four full heddles and four half-heddles for one pair of warp-threads, wherein, as described, the first and third sets of full and half heddles work in unison in connection with one thread, and the third and fourth sets work in unison in connection with the other, 60 65 substantially as shown and set forth.

JOHN H. BENTLEY.
